United States Patent Office

Des. 213,118
Patented Jan. 7, 1969

213,118

PUTTER

Tomohiro Onaka, 5 2-chome Higashitajima, Fukuoka,
Prefecture, Japan

Filed Nov. 24, 1967, Ser. No. 9,521

Claims priority, application Japan Sept. 28, 1967

Term of patent 3½ years

U.S. Cl. D34—5
Int. Cl. D21—03

Fig. 1

Fig. 2

Fig-3   Fig-4

FIG. 1 is a perspective view of a putter showing my new design;

FIG. 2 is a top plan view;

FIG. 3 is a front elevational view; and

FIG. 4 is a side view taken from the left of FIG. 3.

The characteristic feature of my design resides in the double sighting member in combination with the particular golf club shown.

I claim:

The ornamental design for a putter, as shown and described.
